Primary Examiner — Karen S Acker*Assistant Examiner* — Jasmine Mlinarcik(74) *Attorney, Agent, or Firm* — John S. Artz; Dickinson Wright PLLC(57) **CLAIM**

The ornamental design for a scrubbing device, as shown and described.

DESCRIPTION

FIG. 1 is a perspective view of a scrubbing device; FIG. 2 is a front view of the scrubbing device of FIG. 1; FIG. 3 is a back view of the scrubbing device of FIG. 1; FIG. 4 is a left side view of the scrubbing device of FIG. 1; FIG. 5 is a right side view of the scrubbing device of FIG. 1; FIG. 6 is a top view of the scrubbing device of FIG. 1; and, FIG. 7 is a bottom view of the scrubbing device of FIG. 1. The broken lines shown in the drawings illustrate portions of the scrubbing device that form no part of the claimed design.

1 Claim, 3 Drawing Sheets(56)
